(No Model.)

W. M. DOTY.

GUARD GATE FOR SWING BRIDGES.

No. 297,920

Patented Apr. 29, 1884.

UNITED STATES PATENT OFFICE.

WILLIAM M. DOTY, OF CHICAGO, ILLINOIS, ASSIGNOR OF ONE-HALF TO
A. MONTGOMERY WARD, OF SAME PLACE.

GUARD-GATE FOR SWING-BRIDGES.

SPECIFICATION forming part of Letters Patent No. 297,920, dated April 29, 1884.

Application filed December 26, 1883. (No model.)

To all whom it may concern:

Be it known that I, WILLIAM M. DOTY, of Chicago, county of Cook, and State of Illinois, have invented certain new and useful Improvements in Guard-Gates for Swing-Bridges, of which the following is a full, clear, and exact description, that will enable others to make and use the same, reference being had to the accompanying drawings, forming a part 10 of this specification.

This invention relates to improvements in that class of guard or safety gates which are placed on the bridge-approach, and are automatically operated by the opening and closing 15 of the bridge.

Figure 1 is a view of the approach and abutment, looking from the bridge when the same is open, embodying my improved features; Fig. 2, a side elevation of the same, showing 20 the bridge closed; Fig. 3, a modification.

Referring to the drawings, A A' represent the two double gates so constructed and arranged as to close both the driveway B and the foot-passages B' B' on each side of the 25 bridge. The bifurcated posts B' B' are placed on the approach in line with each side of the bridge, as shown in Fig. 1 of the drawings. The two gate-bars C C' are pivoted between these bifurcated or double posts, and are 30 adapted to assume either a vertical or a horizontal position. The outer ends, a a', are a continuation of the gate-bars, and serve to close the foot passage-way at the same time that the driveway is closed. When the bridge 35 is closed, the ends a a' shut in between the supporting posts or uprights B' B', as shown in Fig. 2 and indicated by dotted lines in Fig.

1. The series of pickets a' are pivoted to the gate-bars, and are self-adjusting by the force 40 of gravity. The dotted lines in Fig. 1 indicate the position of the gate or gates when the bridge is closed for traffic. Underneath the bridge-approach, and in line with the gates and supporting-posts, are located the companion 45 transverse levers C' C', the outer ends of which are pivoted at a' to the projecting end of the transverse timber C'. These levers are made very wide near the inner ends, the widened part a' extending downward from 50 the upper line, and are provided with a double

bevel running upward from the slightly-rounded part a', as shown in Fig. 1. These levers are secured with relation to each other by the pin b, attached to the inside lever, C', projecting through the elongated slot b' in 55 the companion lever, C'. By this form of construction and this arrangement the bridge may be swung either way, the two levers moving simultaneously. At a point near the longitudinal center of the levers C' C' are attached 60 the lower ends of the arms b' b', while the upper ends are secured to the projecting lugs b' on the gate-bars just inside of the supporting-posts, as shown in Fig. 1. By means of this connection the gates are raised and lowered 65 by a corresponding movement of the levers C' C'. Underneath the end and transverse center of the bridge, and projecting downward therefrom, is placed the angular lever D, the horizontal part of which is provided with the 70 friction-roller d, adapted to have frictional contact with the under side of the inner beveled ends of the levers C' C', as shown in Fig. 2. The inner ends of the gate-bars are provided on the outer sides with the brackets d', 75 which receive and retain said bars, so that one will not drop below the other when changed to a horizontal position. The beveled ends of the levers C' C' are of sufficient weight to counterbalance the weight of the 80 gates, so that when the bridge is swung open the gates gradually descend from a vertical to a horizontal position, and when the bridge is closed the friction-roller d is brought in contact with the under side of the beveled ends 85 of the levers C' C', raising the same upward, and the gates made to assume a vertical position through the medium of the connecting-arms b' b'.

Fig. 3 is a modification showing arrangement of mechanism whereby the gates may be set back at any distance from the edge of the approach.

Having thus described my invention, what I claim as new, and desire to secure by Letters Patent, is—

1. In a guard-gate for swing-bridges, the combination, with the gates A A', of the arms b' b', and the companion levers C' C', having the outer ends pivoted to the timber C', while 100

the inner ends are widened and beveled, as described, whereby said gates are raised or lowered by the opening and closing of the bridge, substantially as set forth.

5 2. In a guard-gate for swing-bridges, the combination, with a bridge, of the angular lever D , the friction-roller d , the companion levers $C^2 C^3$, the vertical arms $b^2 b^3$, the gates A

A' , and the posts $B^3 B^4$, whereby said gates are automatically opened and closed by the movement of the bridge.

WILLIAM M. DOTY.
